CLAIM

The ornamental design for a fragrance vaporizer, as shown and described.

DESCRIPTION

FIG. 1 is a top perspective view of the fragrance vaporizer. FIG. 2 is a first side elevation view thereof.

FIG. 3 is a second side elevation view thereof.

FIG. 4 is a third side elevation view thereof.

FIG. 5 is a fourth side elevation view thereof.

FIG. 6 is a top plan view thereof; and,

FIG. 7 is a bottom plan view thereof.

Portions of the drawings disclosed in broken lines form no part of the claimed design.
